WINDOW SASH SUPPORTING AND
LOCKING MEANS

Ernest De Nicolais, New York, N. Y.

Application April 25, 1938, Serial No. 204,133

2 Claims. (Cl. 20—42)

This invention relates to an improved window construction of the sliding sash type, the broad object of which is to eliminate the necessity of sash weights, cords and pulleys, while at the same time making provision for the reversal of the sashes to facilitate washing of the outer surface of the panes and the ready removal of the sashes from the window frame and the replacement of the same therein, the invention being a continuation in part of my co-pending application, Serial No. 47,601, filed October 31, 1935, which issued into Letters Patent No. 2,115,139.

The invention comprehends, in a window construction of the indicated character, a frame in which one of a pair of vertical jamb strips between which the sashes are mounted for guided vertical sliding movement in shiftable towards and away from the other to facilitate displacement of the sashes for reversal and the removal and replacement of the same without the necessity of disturbing nails, screws or other similar fastening devices which are considered more or less permanent.

The invention is also directed to means for establishing a sliding and swinging connection between the sashes of the window sill when the same are displaced from the vertical jamb strips so that the sashes may be swung to a reversed position for facilitating the washing of the outer surfaces of the window panes.

As a further feature the invention provides improved interengaging means on the jamb strips and sashes for selectively supporting the sashes in any one of a plurality of positions so as to dispense with sash weights, pulleys and sash cords.

The invention further embodies means for locking one or both sashes in partially opened positions so as to prevent any one from the outside entering through the window.

Other objects are to provide an improved window construction which is comparatively simple in its construction and mode of operation, inexpensive to produce, install and maintain in proper working condition and which is highly efficient for its purpose.

With the above enumerated and other objects in view, reference is now made to the following specification and accompanying drawings in which there is disclosed a preferred embodiment of the invention, while the appended claims cover variations and modifications which fall within the scope of the invention.

In the drawings:

Fig. 1 is an inner front view of an improved

window construction made up in accordance with the invention.

Fig. 2 is an enlarged fragmentary sectional view therethrough taken approximately on a plane indicated by the line 2—2 of Fig. 1. 5

Fig. 3 is a fragmentary sectional perspective view illustrating the lower sash coupled with the window sill and swung to reversed position.

Fig. 4 is a fragmentary vertical sectional view illustrating the sash supporting and locking 10 means.

Fig. 5 is a sectional plan view illustrating in full and dotted lines the lower sash coupled to the sill and in several of its relative positions.

Fig. 6 is a vertical sectional view illustrating 15 the lower sash raised to its uppermost position with the upper sash lowered, coupled to the sill and swung inwardly.

Fig. 7 is an enlarged fragmentary perspective view of the underside of one of the sashes. 20

Referring to the drawings by characters of reference, A designates generally the window frame and B and C the upper and lower sashes which are mounted therein for vertical guided sliding movement. 25

The frame includes a sill 10 and spaced opposite uprights 11 and 12 which are preferably fabricated of various strips to define channel shaped members. The upright 11 includes a fixed jamb strip 13 and the upright 12 includes a shiftable 30 jamb strip 14, each having a central parting strip or bead 15 to separate the upper and lower sashes and between which jamb strips 13 and 14 the sashes B and C are located for guided vertical sliding movement. The movable jamb strip 14 is 35 mounted and guided for lateral shifting towards and away from the fixed jamb strip 13 to admit of the ready removal and replacement of the sashes in the window frame without the necessity of having to remove screws, nails or other similar 40 fastening elements which are of a more or less permanent nature as it will be apparent that retraction or outward lateral movement of the jamb strip 14 will permit of the shifting of the sashes laterally to disengage the same from the guideways at one edge and then their complete 45 removal from the window frame.

As illustrated, the jamb strip 14 is provided with guide pins 16 protruding laterally outward therefrom adjacent the upper and lower ends thereof which pins extend through bearing openings 17 in bearing elements 18 fixedly secured within the upright 12 and which, in the present instance, are disclosed as metal straps fastened 50 55

in place by any suitable means within the channel shaped upright 12.

In order to provide means for facilitating the shifting of the movable jamb strip 14, a crank-shaft 19 having an eccentric crank portion 20 is journaled at its opposite ends in the window frame with the forward end defining a socket terminal 21 exposed at the inner side of the frame for receiving a removable key 22 to turn the crank-shaft. The movable jamb strip 14 is provided intermediate its ends with a lateral outwardly projecting thrust yoke or bail 23 with which the eccentric crank portion 20 is adapted to engage upon turning of the crank-shaft in a clockwise direction for retracting or shifting the movable jamb strip laterally outward when removing and emplacing the sashes in the frame. The eccentric crank portion 20 is adapted to engage with the intermediate portion of the outer surface of the movable jamb strip when the same is retracted and the crank-shaft is turned in a counterclockwise direction.

In order to limit the lateral inward movement of the jamb strip 14, a hooked abutment 24 is provided on the lateral outward surface of the jamb strip 14 with which the eccentric crank portion 20 engages.

Means is provided for selectively supporting the sashes in any one of a plurality of positions without using sash cords, sash weights or pulleys and said means consists of ratchet shaped teeth 25 formed on the lateral inner surfaces of the jamb strips 13 and 14 defining vertically spaced ledges 26 connected by upwardly inclining faces 27. The side styles 28 of the sashes A and B are provided adjacent their lower ends respectively with spring projected latch bars 29 which are normally urged laterally outward into engagement with the teeth 25 by springs 30. The latch bars have socketed inner ends 31, which are disposed within the confines of the side styles 28 of the sashes and which are adapted to receive removable pull knobs 32 for withdrawing the outer terminals of the latch bars 29 from engagement with the teeth 25 when the sashes B and C are to be lowered. In order to facilitate the withdrawal of the latch bars and to provide means for raising and lowering the sashes, bail shaped handles 33 are secured to the side styles 28 in overlying relation to the pull knobs 32. It will be thus observed that by so locating the knobs 32 with reference to the handles, the operator may grasp the handles in the palm of the hand and with the thumb and third and fourth fingers, while the index and second fingers may engage around the pull knobs. In raising the sashes it is not essential to retract the latches as the same will ratchet over the upwardly inclined faces 27 of the teeth.

In order to make provision for locking one or both of the sashes in partially opened position, so as to prevent a person from the outside entering through the window, the jamb strip is provided with keeper openings 34 in the inclined faces 27 immediately above the ledges 26 into which the latch bars 29 are projected by the springs 30. It will, however, be obvious that when the latch bars 29 are disengaged from the lowermost keeper opening 34, it will not be necessary to hold the latch bars retracted as the rapid upward movement of the sash will cause the latch bar terminals to clear the keeper openings before they have an opportunity to enter the same. When it is desired to lock the sashes in partially opened condition, the pull knobs 32

are preferably disengaged from the socketed terminals 31 of the latch bars 29 and as shown, the connection is in the form of a swiveled screw 35 extending through the knob and having an exposed knurled head 36 for effecting the connection and disconnection thereof.

In order to gain access to the pull knobs 32 of the upper sash for withdrawing the terminals of the latch bars 29 when lowering said upper sash, the upper jamb strip 40 of the window frame is provided with a vertically movable section 41 which is normally suspended and guided for vertical movement within the confines of the window frame by upstanding pins 42 which extend through apertured bearing brackets 43. The upper ends of the pins are provided with heads 44 which limit the normal gravitational downward movement of the section 41. Obviously, when the latches of the upper sash are retracted and the sash lowered until the pull knobs 32 are in proximity to the upper rail of the lower sash, the lower sash is then raised until the lower rail is disposed above the pull knobs. The movable strip 41 permits the raising of the lower sash to this position.

In order to provide means for coupling the sashes with the sill 10 so that they may be slidably moved and swung with reference thereto to dispose the outer surfaces of the window panes in a position for washing the same, each sash 30 is provided with a depending stud 45 having an enlarged head 46. The sill is provided with grooves 47 for receiving the lower rails of the sashes and said grooves have secured therein metallic plates 48 each provided with a longitudinal slot 49 to receive the studs 45. The plates are provided at the ends adjacent the movable jamb strip 14 with an enlarged terminal opening 50 to receive therethrough the enlarged heads 46 of the studs.

In use when the sashes are lowered the headed studs 45 protrude through the enlarged openings 50. When it is desired to couple the sashes with the sill 10 for sliding and swinging movements, the sash is lowered to its lowest position, the movable jamb strip 14 is retracted to permit the side edge of the sash remote from said movable jamb strip to be retracted from the fixed jamb strip. The sash may then be swung inwardly and slid so as to reverse the sash for washing the outer surface of the pane.

What is claimed is:

1. A window structure including a frame having vertical jamb strips at the opposite sides thereof, sashes located between said jamb strips for guided vertical sliding movement with reference thereto, means for mounting, guiding and moving one of said jamb strips laterally towards and away from the other to permit of lateral displacement of one side edge of each sash from the jamb strip, slotted guide means in the window sill and headed studs depending from the sashes adapted to engage with the slotted guide means for coupling the sashes to the sill for sliding the same from adjacent one side of the frame to the opposite side thereof and for swinging movement of the sashes to dispose either face thereof inwardly and substantially parallel with the plane of the frame.

2. A window structure including a frame having vertical jamb strips at the opposite sides thereof, upper and lower sashes located between said jamb strips for guided vertical sliding movement with reference thereto, means for mounting, guiding and moving one of said jamb strips lat-

erally towards and away from the other to permit of lateral displacement of one side edge of each sash from the jamb strip, slotted guide means in the window sill and headed studs depending from the sashes adapted to engage with the slotted guide means for coupling the sashes to the sill for sliding and swinging movement, said window frame having an upper jamb strip pro-

vided with a recess for receiving the upper portion of the lower sash to dispose the lower portion thereof above the upper sash when said upper sash is lowered and connected with the slotted guide means to permit of the sliding and swinging movement of said upper sash when in lowered position beneath the lower sash. 5

ERNEST DE NICOLAIS.
